UNITED STATES PATENT OFFICE

WILLIAM JONES, OF TOPEKA, KANSAS

CROSSING SIGNAL

Application filed May 29, 1928. Serial No. 281,488.

This invention relates to crossing signals and more particularly to a mechanically operated crossing signal.

An important object of the invention is to provide in a device of this character a simple and readily constructible crossing signal having means for shifting a signal element from a position at one side of a highway to a position directly over the center of the highway 10 to give a warning signal.

A further object of the invention is to provide a novel and improved control means for such a signalling device whereby the movements of the signal may be governed by a 15 passing train.

These and other objects I attain by the construction shown in the accompanying drawings, wherein for the purpose of illustration is shown a preferred embodiment of 20 my invention and wherein:

Figure 1 is a plan view showing signalling mechanism constructed in accordance with my invention;

Figure 2 is a section on the line 2—2 of 25 Figure 1;

Figure 3 is an enlarged detail view on the line 3—3 of Figure 1;

Figure 4 is a section on the line 4—4 of 30 Figure 3;

Figure 5 is a section on the line 5—5 of Figure 1;

Figure 6 is a detail view showing a spring 35 structure which may be employed in any of the flexible elements to prevent breakage thereof in event of simultaneous operation of two of the control elements.

Referring now more particularly to the drawings, the numeral 10 generally designates a railroad right-of-way and 11 a highway crossing the right-of-way 10. In accordance with my invention, I provide in an angle between the right-of-way and highway, a pair of vertical standards 12 spaced longitudinally of the highway and having pivoted 45 between their upper ends a lever 13, one end of which extends over the highway. The standards 12 have projecting therefrom at the opposite side thereof from the highway and adjacent their upper ends a pair of arms 50 14 which are connected to the corresponding

end of the lever 13 by springs 15, the combined strength of which is just insufficient to lift the opposite end of the lever. The last named end of the lever has at its terminal a stop 17 and upon the lever is longitudinally shiftably mounted a signal element 18 at present disclosed as including a bell 19. This signal element has a roller 20 engaging the lever by means of which it is supported. It will be obvious that if the outer end of the lever is higher than the pivot, this signal will move toward the pivot of the lever and that if the outer end is depressed, the signal will move toward the stop 17. A hood 21 is preferably provided over the lever to 60 protect both the lever and the signal from the weather.

An operating lever 22 is pivoted between the lower ends of the standards 12. The outer end of this lever has its downward movement limited by a stop 23 and the inner end thereof is constantly urged upwardly by springs 24. The combined action of the springs 24 and 15 is more than sufficient to cause an elevation of the signal end of the lever 13 and the inner end of the lever 22. Between the lever 22 and the lever 13 extends a prop 25, the upper end of which is notched to receive the lever 13. It will be obvious that with the inner end of the lever 22 unrestrained, this lever will move upwardly, so that the prop 25 engages the lever 13 to force the signal bearing end thereof upwardly and cause the signal to move toward the standards 12. The extremity of the inner end of the lever is formed with a cam face 25^a which is downwardly disposed.

Opposing the inner end of the lever 22 is a latch casing 26 within which is slidably mounted a carrier 27. This carrier is constantly urged toward the outer end of the latch casing 26 by springs 28 and has formed therein an opening 29 for the passage of the shank 30 of the latch. The latch 31 extends through an opening 32 formed in the inner wall of the casing 26 and has a beveled face 33 opposing the cam face 25^a of the lever 22. A spring 34 extends between the carrier plate 27 and the latch and constantly urges the latch outwardly, this outward movement be- 100

ing limited by a pin 35 extending through the shank of the latch. It will be obvious that if the lever 22 is depressed, the cam face 25^a acting against the beveled face 33 of the latch 5 will force the latch into the casing until the lever has passed when the latch will again spring out and hold the lever in its depressed position until the latch is drawn.

Depression of the lever 22 will, of course, 10 release the support afforded by the prop 25 so that the signal bearing end of the lever 13 may depress and the signal 18 moved to the outer end thereof. In this position, the signal will remain until the latch 33 is withdrawn, again permitting the springs 24 of 15 the lever 22 to come into play and assist the springs 15 to restore the lever 13 to its normal position.

Beneath the lever 22 extends one end of a 20 shaft 36, which extends beneath the right-of-way and is mounted in a suitable bearing 37 at the opposite side thereof. This shaft beneath the lever has a normally horizontally extending arm 38 which is connected with 25 the inner end of the lever 22 by a flexible element 39. Opposing the outer end of the latch casing is a second shaft 40 which likewise extends transversely of the right-of-way 10 and beneath the same. This shaft has in 30 opposition to the end of the latch casing upper and lower vertical arms 41 and 42 which are flexibly connected at 43 to the end of a shank 44^a produced upon the carrier plate 27.

It will be obvious that rotation of the 35 shaft 40 in either direction will cause a pull to be exerted through one or the other of the flexible elements 43 upon the carrier plate so that this carrier plate is withdrawn against the action of the spring 28, with the result 40 that the latch 31 is withdrawn and the lever 22 released. At the far side of the right-of-way from the signal mechanism, the shaft 40 has secured thereto an upstanding striker arm 44 adapted to be engaged by a suitable 45 striker element 45 carried by a train passing over the right-of-way. At the same side of the right-of-way and at the opposite side of the highway from the shaft 40 and at a suitable distance from this highway, a second 50 striker arm 46 is pivoted.

The shaft 36 at the same side of the track is equipped with a downwardly extending arm 47 which is connected to the lower end of the striker element 46, which is in the 55 form of a lever pivoted intermediate its ends, by a flexible element 48 and is further connected to the striker element 44 of the shaft 40 by a flexible element 49.

At the opposite side of the right-of-way 60 from the striker element 44, the shaft 40 is equipped with upper and lower vertically extending arms 50 and 51. The shaft 36 at the same side of the track is equipped with upper and lower vertically extending arms 52 and 65 53. At the same side of the highway 11 but

at the opposite side of the right-of-way 10 from the striker arm 44, a striker arm 54 is disposed which is similar to the striker arm 46. To the lower end of this striker arm is secured a flexible element 55 which is connected at its opposite end to the upper arm 52 of the shaft 36. Upon the shaft 36 at the same side of the right-of-way as the striker 70 54, a third striker lever 56 is provided. This striker lever is connected by a flexible element 75 57 to the upper arm 50 of the shaft 40. The lower arms 51 and 53 of the shafts 40 and 36 are connected by a flexible element 58.

It will be obvious that if a train is approaching in the direction of the arrow of 80 Figure 1, the operating element 45 thereof will engage with the striker lever 56, so that a pull is exerted in the opposite direction to the direction of movement of the train upon the cable 55. This pull causes the shaft 36 to be rotated in the direction of the arrow of Figure 3, with the result that the lever 22 is pulled downwardly to a position where it is held by the latch and the signal lever 13 is released so that the signal may move in a position over the highway 11.

As the train continues its movement, the operating member comes into engagement with the striker lever 56, with the result that a pull upon the cable 57 in the direction of 90 movement of the train results. This causes the shaft 40 to be rotated, withdrawing the latch 31. At the same time, the cable 58, by pulling upon the lower arm 53 of the shaft, causes a rotation of this shaft in the opposite 100 direction to that indicated by the arrow in Figure 3, so that the flexible element 39 is slackened and no resistance to upward movement of the lever 22 may result. If the train is moving in the opposite direction to that indicated by the arrow on Figure 1, it engages the striker member 46 and through the cable 48 and arm 47, causes a rotation of the shaft 36 in the direction of the arrow of Figure 3. Having crossed the right-of-way, the operating element of the shaft comes into engagement with the striker element 44 of the shaft 40, causing this shaft to rotate and the latch 31 to be withdrawn. At the same time, through the cable connection at 49, the shaft 110 36 is rotated to slacken the flexible element 39 connecting the same to the lever 22.

Springs 59 are provided for restoring the striker elements 46, 54 and 56 to their normal position. In the flexible element 49 is inserted a spring cushioning structure which serves to maintain these striker arms in their normal position and which prevents breakage of the flexible element 49 in event the 120 striker elements 54 and 44 should be simultaneously engaged. This structure is only necessary where the signal is employed in connection with the double track.

It will be obvious from the foregoing that 125 signal apparatus of this character may be very 130

readily produced and installed and since it is simple in its construction, will require little attention to maintain the same in proper working order.

5 It will also be obvious that the construction hereinbefore set forth is capable of a certain range of change and modification without materially departing from the spirit of the invention and I accordingly do 10 not limit myself to such specific structure except as hereinafter claimed.

I claim:—

1. In a railway crossing signal for the intersections of highways with railway right-of-ways, a lever pivoted near one end and having its opposite end extending over the highway and normally inclining downwardly and outwardly, a signal mounted upon said end of the lever and shiftable by gravity from 20 end to end thereof, a prop normally maintaining the lever in the position where said end extends upwardly and outwardly over the highway, means operated by a train approaching the intersection for withdrawing the prop, means for latching the prop in withdrawn position, means operated by the train after passing the highway for releasing said latch, and means urging the prop to its lever-supporting position.

2. In a railway crossing signal for the intersections of highways with railway right-of-ways, a lever pivoted near one end and having its opposite end extending over the highway and normally inclining downwardly 35 and outwardly, a signal mounted upon said end of the lever and shiftable by gravity from end to end thereof, a prop engaging the outer end of the first named lever adjacent the pivot thereof, a spring-pressed lever engaging the opposite end of the prop and normally shifting the prop to a position where its outer end is upwardly and outwardly inclined over the highway, means operated by a train approaching the intersection for withdrawing the lever, means for latching the lever in withdrawn position, and means operated by the train after passing over the highway for releasing said latch.

3. In a railway crossing signal for the intersections of highways with railway right-of-ways, a lever pivoted near one end and having its opposite end extending over the highway and normally inclining downwardly and outwardly, a signal mounted upon 55 said end of the lever and shiftable by gravity from end to end thereof, a prop engaging the outer end of the first named lever adjacent the pivot thereof, a spring pressed lever engaging the opposite end of the prop and normally shifting the prop to a position where its outer end is upwardly and outwardly inclined over the highway, a shaft rotated by a train approaching the intersection, said shaft having an arm, a connection between 60 the arm and second lever whereby the second

lever is withdrawn, means for latching the lever in its withdrawn position, and means operated by a train after passing the highway for releasing said latch.

4. In a railway crossing signal for the intersections of highways with railway right-of-ways, a lever pivoted near one end and having its opposite end extending over the highway and normally inclining downwardly and outwardly, a signal mounted upon 70 said end of the lever and shiftable by gravity from end to end thereof, a prop engaging the outer end of the first named lever adjacent the pivot thereof, a spring-pressed lever engaging the opposite end of the prop and normally shifting the prop to a position where its outer end is upwardly and outwardly inclined over the highway, a shaft rotated by a train approaching the intersection, said shaft having an arm, a connection between 75 the arm and second lever whereby the second lever is withdrawn, means for latching the lever in its withdrawn position, and means operated by a train after passing the highway for releasing said latch, said train operated means being duplicated at opposite sides of the right-of-way.

5. In a railway crossing signal for the intersections of highways with railway right-of-ways, a lever pivoted near one end and having its opposite end extending over the highway and normally inclining downwardly and outwardly, a signal mounted upon said end of the lever and shiftable by gravity from 80 end to end thereof, a prop engaging the outer end of the first named lever adjacent the pivot thereof, a spring-pressed lever engaging the opposite end of the prop and normally shifting the prop to a position where its outer end is upwardly and outwardly inclined over the highway, a shaft rotated by a train approaching the intersection, said shaft having an arm, a connection between 85 the arm and second lever whereby the second lever is withdrawn, means for latching the lever in its withdrawn position, and means operated by a train after passing the highway for releasing said latch, said train operated means being duplicated at opposite sides of the right-of-way.

In testimony whereof I hereunto affix my signature.

WILLIAM JONES.
